MEANS FOR GLUING

Lloyd Q. Harris, Brevard, N. C., assignor to Ecusta
Paper Corporation, a corporation of Delaware

Application December 3, 1941, Serial No. 421,443

3 Claims. (Cl. 91—62.5)

My invention relates to means for gluing and more particularly to a device for effecting the gluing or joining together of two sheets with a fine glue line.

An outstanding problem in the manufacture of paper in continuous web form is the joining together of two of the webs in such a manner that the junction therebetween will be substantially indistinguishable and the joined section useful the same as the rest of the web. This problem is particularly pertinent in the manufacture of high quality of diaphanous paper, such as for example, cigarette paper, where it is very difficult to apply a glue line without appreciably damaging the appearance if not the other physical properties of the two sheets or webs of paper at or in the vicinity of their juncture.

The necessity for splicing two paper webs often arises in the rewinding and inspecting operation for the paper. For example, when a large roll of paper is unwound from the original roll and rewound at a distance on another roll so as to provide an opportunity for inspection of the paper as it moves between the two rolls, the defective portions found on such inspection have to be removed. Likewise, taking a section for sample or testing purposes also necessitates the breaking of the web or sheet. These or any other such operations leave a discontinuous sheet and the two ends have to be joined together again so that the rewinding of the paper may continue. The necessity of such operations also arises where it is desired to join one complete roll with another even though no defects occur.

One of the difficulties encountered in splicing or joining together two sheets of thin high quality paper, by means of a glue line, is the accuracy required for applying the glue in a straight fine line. The line must be also perfectly straight to prevent wrinkling or scoring of the paper when the two sheets are joined together. Likewise the line must be fine, that is, a relatively very narrow thin line, to prevent it from showing up in the finished paper. These problems are especially pertinent in the manufacture of cigarette paper and other high quality papers which are finally converted into narrow width bobbins which must have continuous web. It will be apparent that in such cases the glue line section formed in the splicing operation would show up in each narrow bobbin formed from strips of paper cut transversely through the large roll. Therefore, if the splice caused objectionable appearance or other adverse effects each wound bobbin of paper would have a defect along

this portion resulting in substantial waste or unnecessary further labor.

In accordance with my invention I have developed means for applying a glue line which meets all of the above mentioned commercial requirements and overcomes the problems heretofore encountered. I have developed a device which, properly handled, will produce a fine straight line uniformly across the entire width of the web. One of the very desirable characteristics of this device is that it provides an extremely accurate and straight means for applying the glue; as contrasted with means heretofore used which distort or become irregular over a period of time and therefore do not produce the necessary continuous straight fine glue line over the entire width of the paper or other web material.

I have discovered that one of the best means for establishing and maintaining a straight glue line is a wire securely mounted and held under tension. This wire, I have found, is advantageously made of spring steel, which may be chromium plated if desired; although wires of other metals may be used. I have obtained uniformly good results over relatively long periods of time with piano wire of a diameter of about 0.080". It will be understood, however, that this size may vary appreciably with different uses of the device, especially on different types of web material.

One of the most satisfactory methods of applying the glue which I have developed comprises first covering the length of the wire with a relatively large excess of the glue or other adhesive material and then smoothing out the glue to a uniform thin coating on the wire while removing the excess. This can be done by passing the thumb and index finger firmly along the length of the coated wire, or by any other suitable means. The glue coated wire, which is mounted on a suitable support for maintaining it in a firm position, is brought into light contact with one piece of the web material near the end thereof. The surface of the wire permits only a relatively small amount of the glue to be applied to the web material and the fact that the wire is rigidly held in an extremely accurate, straight position causes an equally accurate glue line to be deposited upon the web material. The other piece of web material which is to be joined is then superimposed on the glue line and quickly and firmly pressed along the line so as to cause the two webs to be joined together very accurately. The waste ends of the two joined webs are

then cut away so as to form a very narrow overlap of the two sheets at the glue line. The two joined webs are then ready for continuous rewinding or other desired operations.

The details of construction of my device and mode of use will be clearly understood from the following description taken in conjunction with the accompanying drawings in which like reference characters have been applied to similar parts and in which:

Fig. 1 is a front elevational view of my device for applying a glue line;

Fig. 2 is a top plan view of the device;

Fig. 2A is a sectional view taken along line 2a of Fig. 3; and,

Fig. 3 is a front view of two rolls of web material showing the gluing device in glue applying position.

Referring now to the several figures in the drawings, the wire for applying the glue is identified by reference character 10. This wire, it will be noted, extends substantially the full length of the device at the inner side of the same and is supported only at its two ends by supporting means indicated generally at 11. The frame of this device comprises an elongated member 12 made of wood, or metal, or plastic, or any other suitable material; and metal braces 13. In the usual case three of these braces, that is, one mounted on the outer side and one each at the top and bottom of the frame member 12, will be satisfactory for maintaining this member in accurate straight position. These braces prevent warping, twisting or other distortion of the device and the number and dimensions may therefore vary as desired and in accordance with different sizes and applications of the device.

These braces are fastened at each end by means of supports 14, nuts 15, which are screwed onto the threaded ends 16 of each brace rod, and bolts 17 that are tapped into the flat base portions of the supports 14 and extend across the width of the device. The braces 13 are also supported and maintained in straight position by means of L-shaped supports 18 which are spaced at desired intervals along the device. This arrangement assures a firm secure fastening of the brace rods at each end of the device and provides spaced apart, aligning supports for the brace rods along the length of the device. Since these bracing members are advantageously used on three sides of the device they prevent any appreciable distortion of the framework or of the gluing wire which is mounted on the fourth side.

The gluing wire 10 is held in very accurate alignment by means of the supporting assemblies 11 at each end. Each of these assemblies comprises a substantially U-shaped member 19 which is fastened to the wooden body member 12 by means of bolts 20 tapped into the bottom of the U-shaped member. A longer bolt 21 extends through this member and is held securely by lock nut 22, and the vertical position of the bolt may be varied by adjustment of this nut. The bolt 21 serves as a tensioning means for the glue wire 10. This wire extends through guide holes 19A and 19B formed in the uprights of the U-shaped member 19; also through a hole in the upper end of the bolt 21 as indicated at 23. These holes are just slightly larger than the diameter of the wire 10 so that the latter may be threaded therethrough and may be adjusted lengthwise for tensioning as described below.

The extreme end of the wire 10 after it passes beyond the aperture 19B is fastened around and under the head of a bolt 24 which is tapped into the outer upright end of the U-shaped member 19.

5 The gluing wire is thus held at each end of the device by means of the two assemblies which have just been described and which are located at the respective ends of the device.

To apply the desired tension to the gluing wire 10 and thereby maintain it in very accurate and straight position the bolt 21 is properly adjusted. In the usual case this adjustment is carried out by first fastening the wire at each end under the heads of the bolts 24 and then drawing down

15 on the wire by tightening the nut 22 at one or both ends of the device. As indicated, when the nut 22 is rotated in a clockwise direction, the wire 10 may be pulled down by the bolt 21 to the position 23a indicated by the broken lines. This tightening operation is continued until the desired amount of tension is applied to the wire 10, which in some instances may require the wire to be drawn down into the recess 19c.

20 I have found it of advantage in the use of this device to have the body member 12 extend for a distance beyond the anchors for the glue wire as indicated by the portions 25. These extensions which may be covered as desired with metal plates 26 serve as supports or means of mounting the gluing device in operative position. These extensions 25 may, for example, be placed upon supports on the frame of the rewinding and inspecting machine. When they are so placed, the gluing wire 10 may then be brought accurately and positively in light contact with the web which is to be spliced. This operation is more clearly indicated in Figs. 2A and 3.

25 Referring to these figures, the supporting ends 25 of the device are shown resting upon bracket members 27 of the rewinding machine frame 28, as shown in Fig. 3; and the gluing wire 10 which has been coated with the necessary adhesive material is brought into firm but light contact with the paper web 29 which is normally advanced 30 by metal roll 32. As soon as this straight glue line has been deposited upon the web 29 the glue applying device is removed and the end portion 30 of the other web supplied from the roll 31 is then brought down and pressed on the glue line. The two waste ends of the two web materials 29 and 30 are then cut off and the splicing has been completed in a neat uniform manner so that it is practically indistinguishable and the joined section of paper may be used satisfactorily 35 the same as the rest of the paper.

40 While the device has been described above with particular reference to diaphanous paper, such as for example, cigarette paper, it is to be understood that the use of the device is not limited thereto since it may be applied generally for various types of paper, fabric or other web materials or separate sheets of the same.

45 The word "glue" as used herein for identifying the adhesive material which is used for effecting bonding or splicing of the web or sheet is employed in a generic sense and not by way of limitation. It is intended to cover any and all suitable types of adhesive material including animal, vegetable or synthetic adhesive substances 50 or mixtures thereof.

55 The word "wire" as used herein is employed in a generic sense and is intended to cover all various types and shapes of the glue-applying member. For example, the wire may be of conventional round shape or it may be polygonal

having one or more flat surfaces or one or more rounded surfaces. The shape and dimensions of the wire may vary with different types of glue and with different materials which are to be glued together or with the type and size of the glue line desired.

Various modifications and changes may be made in the means and methods described hereinabove without departing from the scope of this invention, some of the novel features of which are defined in the appended claims.

I claim:

1. A glue applicator of the character described comprising an elongated base member, support members arranged on the respective end portions of said base member, a wire applicator member tightly stretched in spaced parallel and longitudinal relation to said base member between said support members, and bracing means extending closely adjacent to and longitudinally of said base member for preventing distortion thereof.

2. A glue applicator of the character described, comprising an elongated base member, support

members arranged on the respective end portions of said base member, a wire applicator member tightly stretched in spaced parallel and longitudinal relation to said base member between said support members, adjustable means for disposing said wire applicator member in tightly stretched condition, and bracing means extending closely adjacent to and longitudinally of said base member for preventing distortion thereof.

3. A glue applicator of the character described, comprising an elongated base member of rectangular cross-section, support members arranged on one face of said base member at the respective end portions thereof, a wire applicator member tightly stretched in spaced parallel and longitudinal relation to said base member between said support members, adjustable means for disposing said wire applicator member in tightly stretched condition, and bracing means arranged on the remaining faces of said base member and extending closely adjacent to and longitudinally of said base member for preventing distortion thereof.

LLOYD Q. HARRIS.
